UNITED STATES PATENT OFFICE

EMIL PRAZAK, OF ELIZABETH, NEW JERSEY

FOOT AND CUTTING ATTACHMENT FOR HEMSTITCHING MACHINES

Application filed June 4, 1930. Serial No. 459,195.

This invention relates to an improved attachment for hemstitching machines, the object of the invention being to provide a construction which may be quickly applied and quickly removed, and which will function efficiently.

Another object of the invention is to provide an attachment for hemstitching machines wherein a cutting blade or knife is provided and means associated therewith for quickly setting a new knife in place when the old one becomes dulled.

A further object of the invention is to provide an improved attachment for hemstitching machines which is provided with cutting blades wherein the throat plate is provided with a guide and a slot positioned near the needles so that the hemstitching may be cut at the proper time to secure a desired picot effect on each edge of the cut goods.

A still further object of the present invention is to provide an improved form of foot for a hemstitching machine which is particularly adapted to allow ample movement of the cutting knife and piercers and needles, so that the parts may function in a close group.

In the accompanying drawings—

Figure 1 is a fragmentary side view of a hemstitching machine illustrating an attachment embodying the invention applied thereto, certain parts being broken away for better illustrating the structure;

Figure 2 is a top plan view of the presser foot shown in Figure 1;

Figure 3 is a front view of the presser foot shown in Figure 1;

Figure 4 is a top plan view of the throat plate and feeder shown in Figure 1;

Figure 5 is a front view of the piercer holder shown in Figure 1, together with a cutting blade or knife and its supporting arm;

Figure 6 is a detailed perspective view of the knife and its supporting arm;

Figure 7 is a sectional view through Figure 5 on the line 7—7;

Figure 8 is a plan view of a small piece

of fabric showing how the stitching is applied and then cut to form a picot on the two cut edges, the knife and part of the piercer being shown in connection therewith.

Referring to the accompanying drawings 55 by numerals, 1 indicates a conventional type of hemstitching machine, provided with the usual reciprocating bar 2 carrying at its lower end an auxiliary piercer 3 and a pair of needles 4. The auxiliary piercer 3 and the needles 4 are movable through a presser foot 5 as the machine functions. Coacting with the presser foot 5 is a feeder or feed dog 6 formed in a conventional way with a slot 7 which extends to a point near the 60 needle opening in the throat plate and is usual for a device of this kind.

As shown in Figure 1, the guide 8 is provided with a long foot 9 carrying two screws 10. It will be noted in this structure that 70 the entire support of the guide 8 is on the side opposite the slot 7. A piercer bar 11 forms part of the machine 1 and carries a specially formed piercer holder 12, said holder carrying the piercer 13 located between the needles 4 and adapted to spread the stitches made by these needles. The function of the piercer 13 is usual and therefore forms no part of the present invention except in combination. The invention is directed to the various parts and the attachment which are adapted to assist in forming the picot edging 14, as shown on a piece of fabric 15 in Figure 8. After each time the 75 needles 4 function the piercer 13 spreads the cloth or fabric, and immediately thereafter the knife or cutting blade 16 severs the threads.

From Figure 5 it will be noted that the piercer holder 12 has a laterally extending 90 arm 17 having a countersunk 18 and a slot 19. Also arm 17 is provided with a longitudinally arranged groove 20 for receiving the bead 21 of the knife arm 22. Knife arm 22 is provided with a socket 23 for receiving 95 the end 24 of knife 16, whereby the screw 25 may rigidly clamp the knife to arm 22. Arm 22 is provided with a threaded aperture 26 for receiving the screw 27 which extends through slot 19, whereby arm 22 100

may be adjusted longitudinally of arm 17 and thereby adjust the position of knife 16.

- In order that arm 22 may be readily grasped by the thumb and fingers a roughened section 28 is provided, said roughened section consisting of grooves cut into the arm. A screw 29 is threaded into arm 22 and extends through the slot 30 in the abutment or stop 31. After the knife 16 has been once properly adjusted and screw 27 tightened the abutment 31 is moved until it presses tightly against the piercer holder 12, as shown in Figure 5, and then screw 29 is tightened. After this has been once done 10 the abutment is usually left in its adjusted position and screw 27 removed when it is desired to remove the arm 22 for replacing a blade 16 or for any other purpose. When it is desired to replace the arm 22 the same may 15 be merely held in approximately correct position so that the screw 27 may be inserted. Before this screw is tightened arm 22 is slid over to the right in Figure 5 until the abutment 31 presses tightly against the holder 12 and then screw 27 is tightened. In this 20 way the parts may be quickly and accurately adjusted so that the blade 16 will properly extend through the slot 7 during the operation of the machine.
- As shown in Figures 2 and 3, foot 5 is 25 divided into two parts and is formed with a slot 32 through which the knife 16 moves as the machine functions. As shown in Figure 3 the foot section 5' is provided with an upwardly extending standard 33 merging into a block 34 carrying a pin 35 on which the standard 36 slides, said standard being integral with the foot section 5' and having a slot 37 therein for accommodating this 30 pin. A set screw 38 acts to lock the pin against movement in the extension 39 of block 34. Block 34 is provided with an aperture 40 for accommodating a bar 41 which is clamped to the block by a set screw 42. Arm 36' extending from block 34 has a laterally extending section 43 provided with an aperture through which bar 41 extends, and a set screw 44 clamps extension 45 to the bar 41.
- A small plate 45 is secured by a screw or otherwise to the block 34 and also to the auxiliary block 34', which is preferably integral with block 34 and is connected therewith by the auxiliary standard 36'. Auxiliary block 34' is provided with an aperture through which the bar 41 extends. The block 34' is provided with a slot at the rear so that it may be clamped to bar 41 by a suitable clamping screw 46. In this way 50 the two parts are held together so as to function as a single structure, and at the same time present a slot 32 for knife 16. By providing the narrow bar 45 ample space is left for the arm 22 and associated parts to 55 function as the knife is moved up and down.

In operation the auxiliary piercer 3 upon descent of the bar 2 cuts a hole, as indicated by the numeral 47 in Figure 8, in the fabric 15. As this perforation is fed under the needles its edges are stitched, as indicated 60 at 48, and the threads are pushed apart by the piercer 13 so that the hemstitching includes a series of perforations stitched at their edges and a series of cross threads, such as 49, between the perforations. It is the 65 function of the knife 16 upon its descent to cut these threads and thereby simultaneously form two picot edges, such as 14 as shown in Figure 8.

What I claim is—

1. The combination with a hemstitching machine including a presser foot and a piercer bar, of a piercer holder carried by said bar and formed with a supporting arm, said supporting arm being formed with a longitudinally positioned groove in one side and a slot extending through the arm, said slot being spaced from said groove, a knife movable through said presser foot, a knife arm carrying said knife, said knife arm being formed with a bead slidably fitting in said groove, a threaded aperture spaced from said bead, and a clamping screw extending through the slot in said supporting arm into said threaded aperture for adjustably clamping the knife arm to the supporting arm and adjustable means carried by said knife arm adjacent the end opposite the knife, said adjustable means being positioned to engage said supporting arm and limit the sliding movement of said knife arm in respect to said supporting arm.
2. The combination with a hemstitching machine including a presser foot, a reciprocating piercer bar and a holder bar, of a supporting arm carried by the holder bar, a knife movable through said presser foot, a knife arm adapted to be secured to said supporting arm, means for securing said knife to said knife arm, means for adjustably securing the knife arm to said supporting arm, and an adjustable stop carried by said knife arm adapted to limit the adjustment of said knife arm in one direction.
3. In an attachment for a hemstitching machine, a piercer holder having a laterally extending piercer arm, a knife, a knife arm mounted on said piercer arm and adjustable longitudinally thereof, said knife arm being formed with a socket in one end adapted to receive one end of said knife, and a threaded screw-receiving opening to receive a supporting screw, and a screw extending through one end of said knife into said knife arm acting to clamp the knife in said socket and a stop member adjustably mounted on said knife arm for limiting the adjustable movement of the knife arm in one direction.
4. In an attachment for a hemstitching machine, the combination with a piercer

holder having a groove in one face, of a knife, a knife arm having a longitudinally positioned bead adapted to slidingly fit into said groove for preventing rotation of said 5 knife arm in respect to said holder, means for rigidly securing the knife to said knife arm, an adjustable stop carried by the knife arm coacting with one end of said holder for limiting the movement of the knife arm in 10 one direction and a clamping screw for clamping said knife arm and said holder together, said screw when functioning causing said bead in turn to function.

5. In an attachment for a hemstitching 15 machine, a knife arm, a knife removably secured to one end of said arm, said arm being

provided with a roughened end presenting a hand grip for holding the arm, a bead carried by said knife arm adapted to prevent rotation of said arm and a stop mounted on said roughened end adjusted longitudinally 70 of said arm.

6. In an attachment for a hemstitching machine, a knife, a knife arm, means for rigidly securing said knife to said knife arm, said arm being provided at the end opposite the knife with a roughened portion acting as a hand grip, and a stop adjustably mounted on said arm adjacent said roughened portion.
